DRAFTING TEMPLATE

Rush Jordan, Dillon, Mont.

Application August 17, 1951, Serial No. 16,314

Term of patent 14 years

(Cl. D52—1)

To all whom it may concern:

Be it known that I, Rush Jordan, a citizen of the United States, residing at Dillon, State of Montana, have invented a new, original, and ornamental Design for a Drafting Template, of which the following is a specification, reference being made to the accompanying drawings, forming a part hereof, wherein:

Figure 1 is a perspective view of a drafting template embodying my new design.

Figure 2 is a perspective view taken at right angles to the view of Figure 1.

Figure 3 is a section taken at the line 3-3 in Figure 1.

I claim:

The ornamental design for a drafting template, substantially as shown.

RUSH JORDAN.
